UNITED STATES PATENT OFFICE

2,507,352

PUMP JACK

Daniel R. Scheles, Oak Park, Ill., assignor to
 Aeromotor Company, Chicago, Ill., a corporation
 of Illinois

Application November 23, 1945, Serial No. 630,458

4 Claims. (Cl. 74—41)

1

My invention has to do with improvements in pump jacks, or power heads, adapted to be used to operate the piston of a pump.

An object of my invention is to provide a pump jack having a bottom casing, adapted to contain a supply of lubricating oil, and a pivotally, or removably, mounted top casing, having mounted thereon all the operating mechanism of the jack which it is desirable to have operating in the oil bath within the casing, whereby the operating mechanism may be readily removed from the casing for inspection or repair.

A further object of my invention is to provide, in a pump jack, a novel actuating arm having an arcuate movement, supported in and projecting through a downwardly directed aperture in the casing top, which is located at a distance above an oil bath in the casing bottom, whereby effective operation is obtained without loss of oil through the aperture.

These and other objects will be apparent from the preferred form of my invention which is illustrated, by way of example, in the accompanying drawings, wherein:

Fig. 1 is an elevation of my pump jack connected in operative relation to a conventional pump;

Fig. 2 is a plan of my pump jack with parts broken away; and

Fig. 3 is a section on the line 3—3 of Fig. 2.

As illustrated in Fig. 1, my pump jack is adapted to be used with a pump head 10 having a spout 11, a pump handle 12, and a piston rod 13. For hand operation the piston rod 13 is reciprocated by movement of the pump handle 12. To adapt the pump for power operation pitmans 14 are provided which are connected in a conventional manner to the piston rod 13. The pump handle 12 is disconnected from the piston rod 13 when it is desired to operate the piston rod 13 by connecting the pitmans 14 to the pump jack.

My pump jack comprises a bottom casing member 15 forming a chamber for a suitable lubricant and a top casing member 16, which supports the operating mechanism thereon. The bottom casing member 15 is provided with a pair of inverted U-shaped socket members 17 while the top casing member 16 is provided with pairs of spaced apertures 18 which receive therein the threaded legs 19 of U-shaped pintles 20 journaled in the socket members 17 and provided with fastening nuts 21 on the legs 19.

A laterally extending shaft member 22 is rigidly secured in the bracket 23 depending from the top casing member 16. Rotatably mounted on each end of the shaft member 22 is a large gear

2

24. A driving shaft 25 is supported from the top casing member 16 by a depending bearing member 26. Keyed to the driving shaft 25 are pinions 27 which engage with and drive the gears 24. 5 The driving shaft 25 extends outwardly through the side of the top casing member 16 and pulley wheel 28 is keyed on the outward end thereof. The motor 29 having a motor pulley 30 supplies power to the pulley wheel 28 by means of a belt 31.

10 The motor 29 is supported on a platform 32 and secured thereto by bolts 33. The platform 32 is pivotally mounted at 34 on the top casing member 16. A laterally extending portion 35 on the platform 32 is provided to receive a threaded bolt 36 having one end secured in a socket 37 on the top casing member 16 and provided with nuts 38, by means of which the platform 32 may be adjusted to provide tension in the belt 31.

15 20 A reciprocating arm or pitman 39 is eccentrically pivoted at one end 40 to each of the gears 24 while the other end of each arm 39 is pivoted at 41 to a bell crank actuating member 42. The bell crank 42 is mounted on a shaft 43 which is journaled in brackets 44 depending from the top casing member 16. The upwardly directed arm 45 of the bell crank member 42 terminates in an arcuate portion 46 to which is attached the arcuate portion 47 of an actuating arm 48. The arm 48 extends through an aperture 49 in the top casing member 16. The actuating arm 48 is provided with a laterally extending portion 50 which is adapted to be pivotally secured at 51 to the bottom of the pitman 14.

25 30 35 The actuating mechanism of my pump jack is supported from the top casing member 16 and projects down into the bottom casing member 15 where it receives adequate lubrication from the oil 52 in the bottom casing member. The top casing member 16 is provided around its edge with a sealing channel 53 which engages over the top edge of the bottom casing 15. The operation of the parts within the casing agitates the oil 52 and carries it to all the bearing points. The structure is designed to prevent loss of oil be-

40 45 50 55 cause all operating members which extend out of the casing are arranged to extend through apertures in the top casing member 16, well above the level of the oil bath 52 in the bottom casing 15. Access to all the working parts, either for repair or replacement, is obtained merely by hinging the top casing member 16 about its pintles 20 or if desired by removing the top casing member 16 entirely.

While I have described specific details of construction and arrangement of the parts of my

device, it will be understood that other details of construction and arrangement may be resorted to within the scope of my invention.

I claim:

1. In a power head for a pump, the combination with a casing having a removable cover member provided with an outwardly and downwardly facing aperture, a power driven pinion, a gear wheel and an oscillating actuator supported on the cover member within the casing, an eccentric drive connecting the gear wheel and the actuator, and an arm having a curved portion connected to the actuator inside the casing and extending through the aperture in the cover member and having a laterally extending portion adapted to be connected to a pitman on the pump.

2. In a pump jack for operating a pump which is provided with a piston rod and pitman connected thereto, a casing having a removable top member provided with a downwardly facing aperture, operating arms connected to said pitman, said arms having portions extending laterally and other portions extending upwardly and inwardly through said aperture into the top cover member, means mounted within said top cover member and connected to the upwardly and inwardly extending portions of said operating arms for oscillating said operating arms, power drive means located outside of said casing, and means extending into said top cover member and connecting said power drive means with said means for oscillating said operating arms.

3. In a pump jack for operating a pump which is provided with a piston rod and a pitman connected thereto, a casing having a top cover member hingedly connected thereto, said cover member having a portion extending over a side of the casing adjacent the pump, said extending portion of said cover member having a downwardly directed aperture, operating arms con-

5

nected to said pitman, said operating arms having a laterally extending portion and an upwardly curved portion projecting upwardly through said aperture and into said cover member, means mounted within said cover member and extending into said casing for oscillating said operating arms, said curved portion of said operating arms being connected to said oscillating means, power drive means located outside of said casing, and means extending into said cover member for connecting said power drive means with said oscillating means for said operating arms.

4. In a power head for a pump provided with a pitman, a casing having a top provided with a portion overhanging the bottom of the casing and a downwardly facing aperture therein, power mechanism mounted in said casing, an oscillating actuator device supported in said casing, said actuator having an arm connected to said power mechanism, and said actuator having another arm extending upwardly into said top and then outwardly and downwardly through said downwardly facing aperture in said top and a laterally extending portion on said last mentioned arm for connection with the pitman on the pump whereby said last mentioned arm is moved in an arcuate path by operation of said power mechanism to oscillate said pitman.

DANIEL R. SCHOLES.
